US0D1073937S

(12) **United States Design Patent** (10) **Patent No.:** **US D1,073,937 S**
(45) **Date of Patent:** **** May 6, 2025**

(54) **PERFUSION INSTRUMENT**

(71) Applicant: **Akihiro Maruo**, Himeji (JP)

(72) Inventor: **Akihiro Maruo**, Himeji (JP)

(**) Term: **15 Years**

(21) Appl. No.: **29/865,655**

(22) Filed: **Aug. 5, 2022**

(51) LOC (15) Cl. **24-02**

(52) U.S. Cl.

CLAIM

The ornamental design for a perfusion instrument as shown and described.

DESCRIPTION

FIG. 1 is a perspective view of a perfusion instrument showing my new design;

FIG. 2 is a front view thereof;

FIG. 3 is a top view thereof;

FIG. 4 is a bottom view thereof;

FIG. 5 is a rear view thereof;

FIG. 6 is a right side view thereof;

FIG. 7 is a left side view thereof; and,

FIG. 8 is a cross section along line 8-8 in FIG. 3.
